UNITED STATES PATENT OFFICE

2,004,736

ELECTROSTATIC LOUD SPEAKER

Adolph A. Thomas, New York, N. Y., assignor to
Radio Corporation of America, New York,
N. Y., a corporation of Delaware

Application April 5, 1929, Serial No. 352,642

2 Claims. (Cl. 181—31)

My invention is for an electrostatic loud-speaker provided with a pair of diaphragms adapted to operate most efficiently on different bands of frequencies, so that the entire audible 5 scale of tones is faithfully reproduced. A large diaphragm accentuates the lower frequencies, and a small diaphragm emphasizes the higher frequencies. For this purpose, each condenser unit is subjected to potential variations in a circuit 10 adapted to pass certain bands of frequencies. The two diaphragms are preferably mounted in tensioned condition on opposite sides of a flat frame in electrostatic relation to a pair of stationary plates. The supporting frame may be 15 rotatable on a base, so that the diaphragms can be turned in the desired direction.

The novel features and practical advantages 20 of my invention will be understood from a description of the accompanying drawing, in which—

Fig. 1 shows a face view of a condenser speaker constructed in accordance with my invention, certain parts being broken away for clearness and lack of space.

Fig. 2 represents a vertical section on line 2—2 of Fig. 1;

Fig. 3 is an enlarged fragmentary section to show certain structural details;

Fig. 4 is an enlarged bottom view of the central 30 portion of the supporting base or stand; and

Fig. 5 is a diagram of circuit connections.

A circular frame 10 is provided on opposite faces with a pair of circular recesses 12 and 13, in which are mounted fixed condenser plates 35 or disks 14 and 15. The frame 10 may be molded as a single piece of insulating material, such as bakelite, earthenware, fiber, hard rubber and others along the same line. The condenser plates 14 and 15 may conveniently be cut or 40 stamped from stiff sheets of metal like aluminum, duralumin, brass and other metals and alloys that are familiar to the electrical expert. If the condenser plates 14 and 15 are inserted in their respective recesses with a tight frictional 45 fit, no additional fastening means are necessary. It will be noticed in Figs. 2 and 3 that the surrounding wall of each recess projects slightly beyond the outer surface of the associated plate. The purpose of this feature will later be 50 explained. In the present embodiment, the condenser plate 14 is considerably larger than plate 15, so that diaphragms of correspondingly different size may be mounted in operative relation 55 to the fixed plates to improve the reproduction

of the instrument. This will be understood as the description proceeds.

The circular recesses 12 and 13 in frame 10 are surrounded by a pair of annular grooves 16 and 17, which are preferably tapered or conical in cross-section. Two vibratory electrodes 18 and 19 are mounted on the opposite faces of frame 10 over the fixed plates 14 and 15. A simple way to fasten the vibratory electrodes 18 and 19 in place is by means of rings 20 and 21, 10 which engage the edges of the electrodes and are secured to the frame by screws 22 or otherwise. The members 18 and 19 are thin elastic membranes of metal adapted to operate as loud-speaking diaphragms. Among materials suitable 15 for this purpose I may mention nickel, invar (an alloy of nickel and steel), duralumin, bronze, steel, and similar metals and alloys. A diaphragm of invar has the advantage that it is not affected by changes in temperature. In the present instance, the inner side of each membrane is covered with insulation 23, which may be silk, cheesecloth, netting, rubber cement, a sheet of India rubber, and other materials along the same line. Instead of providing the vibratory membranes 18 and 19 with an insulating sheet or coating, the adjacent faces of the fixed condenser plates 14 and 15 may be insulated in the same manner to prevent short-circuiting of the instrument during the vibration of the membranes. 20

The membranes 18 and 19 are mounted in stretched condition by the peripheral rings 20 and 21, but it is desirable to increase the tension of the membranes to a greater degree than 35 can ordinarily be obtained by the clamping rings alone. For this purpose I use a pair of wedge-shaped rings 24 and 25 adapted to fit into the correspondingly shaped grooves 16 and 17. Screws 26 or other fastening means hold the 40 rings 24 and 25 firmly in place. It is clear from Figs. 2 and 3 that, when the wedge-shaped rings 24 and 25 are forced into the grooves 16 and 17 over the membranes 18 and 19, the latter are drawn into the grooves and thereby stretch radially in all directions to the desired degree of tension. This may be regulated by the position of the rings, the tension of the membranes being greatest when the rings are forced fully 45 into the grooves. I have previously mentioned 50 that the shoulders around the circular recesses 12 and 13 project slightly beyond the condenser plates 14 and 15. The purpose of this construction is to maintain the tensioned membranes 18 and 19 spaced a predetermined amount from 55

the adjacent fixed plates, as indicated at 27 in Fig. 3. It will be understood, of course, that this figure is greatly exaggerated, particularly as to the thickness of the vibratory membrane and its separation from the fixed electrode. The air space 27 is not absolutely necessary, because the two condenser elements of each unit need only be separated by the insulating sheet or covering 23, which in that case should be sufficiently elastic to permit free vibration of the membranes under the action of electrostatic attraction and repulsion. The metallic membranes 18 and 19 may also be formed by coating the tensioned insulating sheets 23 on the outside with metal foil or paint, such as are available in the market.

The circular supporting frame 10 is provided with a pair of peripheral flanges 28 for receiving screws 29, which hold a pair of screens 30 in place. These screens may be loosely woven cloth or suitable grilles surrounded each by a ring 31 through which the screws 29 pass. The purpose of screens 30 is not only to hide the membranes 18 and 19, but to prevent a person from accidentally touching the charged electrodes. It is understood, of course, that the screens or grilles 30 are sufficiently open to permit the free passage of sound. In some cases it may be desirable to mount the circular frame 10 rotatably on a suitable base or stand 32. In Fig. 2 there is a tubular mounting 33 fixed at its upper end in frame 10 and at its lower end projecting rotatably into a hub or bushing 34 in base 32. The tube 33 has a lateral flange or shoulder 35, which rests on the bushing 34 to permit easy rotation of frame 10 and tube 33. A cross-pin 36 in the lower end of tube 33 engages a stop 37 in base 32 to limit the rotary movement of frame 10. The advantage of the rotary mounting of frame 10 is that the diaphragms 18 and 19 can be turned in any desired direction. The various conductors which are electrically connected to the condenser elements are concealed in a passage 10' in frame 10 and pass through the tube 33 into the base.

A simplified diagram of circuit connections for the condenser units 14-18 and 15-19 is illustrated in Fig. 5. A generator 38 of substantially constant potential is connected at one side to the fixed condenser plates 14 and 15, and at the other side to the vibratory membranes 18 and 19. Inductance or resistance devices 39 of the required electrical values are inserted in the polarizing circuit to prevent the variable signal voltage from passing through the generator circuit. It will be understood that 38 represents any suitable source of polarizing voltage for the condenser elements, such as a storage battery or the house-lighting circuit. If the latter operates on alternating current, it will, of course, be necessary to interpose a rectifier. The signal voltage impressed on the condenser elements is supplied in this instance through a transformer 40 having a primary coil 41 and two secondary coils 42 and 43. The primary coil 41 is connected in the output circuit of a suitable ampli-

fying system, many examples of which are known in the radio art. The opposite sides of coil 42 are connected by wires 44 and 45 to the condenser elements 14 and 18, respectively. One side of secondary coil 43 is connected by wire 46 to the fixed plate 15, and the other end of the coil is connected by wire 47 to the vibratory membrane 19. A condenser 48 is shunted across the secondary coil 42, and an inductance 49 is connected across the secondary coil 43. The electrical values of devices 48 and 49 are so chosen that low frequencies of potential variation are impressed on the condenser units 14-18, while high frequencies are impressed on the condenser units 15-19. By making the parts 48 and 49 adjustable, they are easily brought to the required values.

As a result of the circuit arrangement above described, the small diaphragm 19 reproduces the high frequencies, while the large diaphragm 18 brings out the low frequencies. There will, of course, be intermediate frequency bands that will simultaneously affect both diaphragms, but that does not interfere with the operation of diaphragms 18 and 19 in accentuating, respectively, the lower and upper portions of the musical scale. The diameters and tension of the two diaphragms 18 and 19 are so chosen that the first diaphragm has a low natural frequency and the second diaphragm a high natural frequency. It is not necessary that the diaphragms 18 and 19 shall always be of different sizes, because they may have the same diameter and yet be capable of accentuating different bands of frequencies. As acoustical experts know, the quality of sound produced by a diaphragm depends to some extent on the material and elasticity of the diaphragm. The membranes 18 and 19 need not be circular in all cases, for they can be made rectangular, in which event they would be supported under tension at two opposite ends.

Although I have shown and described a specific construction, I want it understood that my invention is not limited to the details set forth. It is to be expected that changes and modifications will occur to others without departing from the scope of the invention as defined in the appended claims.

I claim as my invention:

1. An acoustic device, comprising in combination, a housing including a disc shaped member, a diaphragm, supporting members attached to said housing for supporting said diaphragm, and a grille mounted opposite said housing for protecting the diaphragm, supports for said grille, said supports for the grille being independent of the supports carrying the diaphragm.

2. In an acoustic device, a frame, a driving movement mounted on said frame, a diaphragm, a grille, and a plurality of rows of supports, one of said rows of supports supporting the diaphragm and another row the grille whereby the grille and the diaphragm are mounted on independent supports.

ADOLPH A. THOMAS.
